INVENTOR
M.C. KELLY
BY HIS ATTORNEY

James F. Williamson

UNITED STATES PATENT OFFICE.

MICHAEL C. KELLY, OF MINNEAPOLIS, MINNESOTA.

NECKTIE.

Application filed January 4, 1924. Serial No. 684,356.

To all whom it may concern:

Be it known that I, MICHAEL C. KELLY, a citizen of the United States, residing at Minneapolis, in the county of Hennepin and 5 State of Minnesota, have invented certain new and useful Improvements in Neckties; and I do hereby declare the following to be a full, clear, and exact description of the invention, such as will enable others skilled 10 in the art to which it appertains to make and use the same.

This invention relates to a necktie and particularly to a tie adapted to be tied by the wearer, such as a four-in-hand tie. It 15 is desirable from several view points to have certain four-in-hand ties constructed with the grain or texture of the cloth and the pattern thereof, especially striped patterns, extending diagonally across the longitudinal 20 center line of the tie. It has been the common practice to cut such ties from a sheet or bolt of the goods, using patterns which were laid out on the goods in a diagonal direction relatively to the pattern or texture 25 of the goods. Such patterns generally have been formed with reversely curved edges, particularly adjacent their ends, so that when the tie was cut out from the goods there would be a fullness on one side of the 30 tie which would have to be taken up in the stitching. This fact, together with the fact that the ties were not laid out with a center line on the pattern at the correct angle with the grain or texture of the goods, resulted in 35 an uneven bias in the finished tie, which has been found to be very objectionable.

It is an object of this invention, therefore, to provide a tie the longitudinal center line 40 of which extends on a bias of 45 degrees or, in other words, extends at 45 degrees to the warp of the goods, whereby the threads are of equal length on each side of the longitudinal center line and twisting of the tie due to longitudinal pulling movement there- 45 of is prevented.

It is a further object of the invention to provide a tie cut from a pattern in which the side edges are rectilinear and make equal angles with the longitudinal center line of 50 the pattern and preferably are also of equal length.

It is still another object of the invention to provide a method of laying out the ties on the goods and cutting out the same so

that the goods is efficiently used and a tie 55 having proper bias is produced.

These and other objects and advantages of the invention will be fully set forth in the following description made in connection with the accompanying drawings in 60 which like reference characters refer to the same parts throughout the different views, and in which,

Fig. 1 is a plan view showing a strip of goods with the patterns laid out thereon. 65

Fig. 2 is a plan view of the tie as cut from the goods before the same is folded.

Fig. 3 is a cross section of a partially completed tie.

Fig. 4 is a cross section also showing the 70 tie just before completion.

Fig. 5 is a plan view of the front side of the completed tie.

Fig. 6 is a plan view of the rear side of the completed tie. 75

Referring to the drawings, a sheet of material suitable for ties, such as silk, satin, or other material, is indicated as 1, on which piece of goods the figures, such as stripes, are extended vertically or horizontally. The 80 pattern or the shape in which the ties are cut from the goods are indicated on said sheet as 2. Such patterns, it will be noted, have side edges 2^a which are rectilinear from the line 1^a to the large part of the pattern 85 and diverge at equal angles from the longitudinal center line 2^b indicated as a dash and dot line. The side edges 2^a of the pattern are also substantially of equal length terminating at the corners 2^c, the terminal part 90 of the tie 2^d being pointed or triangular in shape, which triangular portion has an extra strip 2^e along one side thereof. One of the side edges 2^a continues as a straight line to the smaller end of the pattern, 95 but the other edge 2^a extends slightly outward from the line 1^a to the small end of the tie, said side thus forming a very obtuse angle with its vertex at the line 1^a

for a purpose to be later described. The 100 patterns 2 are laid out on the goods with their longitudinal center lines 2^b extending at an angle of substantially 45 degrees with the warp threads 5, and consequently to the woof threads 6 which extend 105 at right angles thereto, and thus, with the figure of the goods so that if the figure comprises stripes, the stripes extending diag-

onally across the pattern. Two of the patterns 2 are laid out in contacting reverse relation and the patterns at each side thereof are suitably spaced so that pieces 3 will be 5 formed therebetween, which pieces are divided along the line 4. The pieces 3 are used to form the small ends of the ties and the ends 3^a thereof are also pointed or triangular in shape and have a projecting strip 3^b at one side thereof. It will thus be seen that practically all of the goods is used and there is very little waste material. The ties, as cut from the goods, along the edge of the patterns 2 and 3 are then arranged as indicated 10 in Fig. 2. The tapered ends of the portions 3 are overlapped along one side with the tapered end of the portion 2, the side edge 2^a on which the portion 3 is overlapped being the side having the obtuse 15 angle therein, said angle providing a narrow strip of material adapted to be stitched to the overlapping portion of the piece 3. The narrow strips 2^a and 3^b are folded over and stitched or hemmed as these parts do 20 not extend along the formed selvage of the strip of goods, as do the opposite sides of portions 2^a and 3^b.

The tie, as shown in Fig. 2, is now folded on its longitudinal center line and stitched 30 along the folded edge, as indicated in Fig. 3, which represents a cross section of the tie so folded and stitched. The tie is now turned inside out so that the stitched edges are on the interior thereof and the tie is 35 then folded so that the stitched edges extend in the longitudinal center of the rear side thereof, as shown in Fig. 4 and Fig. 6. The tie is now pressed in this condition and the finished tie appears, as shown in Fig. 5 and 40 Fig. 6. By so cutting and folding the tie, the longitudinal center line of the pattern 2 now becomes the center line of the main or tying portion of the finished tie.

Applicant's method, therefore, results in a 45 tie in which the longitudinal center line extends substantially at 45 degrees to the texture or warp of the goods and the stripes, if there are stripes, in the figure, also extend diagonally across the tie. When the longitudinal center line of the tie thus makes an 50 angle of 45 degrees to the warp threads it, of course, will make the same angle with the woof threads which are at right angles to the warp threads. This results in the 55 length of a warp thread 5 passing through any point on the longitudinal center line being the same length as the woof thread 6 which passes through said point. When a longitudinal stress or pull is placed on the 60 tie the stress is thus along the bisector of the angle of the warp and woof threads and the same stress is placed on the warp threads as is placed on the woof threads. It will 65 readily be seen that this is not true if the longitudinal center line of the tie is at

any other angle than 45 degrees. If the center line is not at an angle of 45 degrees one side of the tie will be stretched more than the other by a pull and the tie will twist or curl. With the longitudinal center line at 70 45 degrees, however, the pull on both sides of the threads is equalized and one side of the tie is not stretched more than the other and the tie will not twist when pulled upon. It is well known that four-in-hand ties, 75 when cut diagonally of the goods, soon twist and get out of shape becoming practically strings instead of flat pieces of the goods. The tie of the present invention will not twist but will retain its flat and proper 80 shape. The twisting in ties of the prior art, as above set forth is caused by an unequal bias in the tie or in other words, because the warp and woof threads passing through a point on the center line are not of equal 85 length so that there is an unequal strain on the threads at the different sides of the tie. With applicant's tie, as above stated, the warp or woof threads passing through a point on the longitudinal center line of the 90 tie are of the same length and there will be equal strains produced at each side of the tie when the same is pulled upon. The edges of the blank being straight throughout the main portion of the tie, there is no fullness 95 of said edges to be gathered or tucked in which would cause unequal strains at the edges of the tie.

From the above description it is seen that applicant has provided a novel and ingenious method of producing a tie having the proper bias. Tests have been made on the tie and it has been demonstrated that the tie will not twist even when a heavy pull or tension is applied longitudinally thereof. 100 With ties of the prior art, a very small pull or tension only was necessary to cause twisting thereof. A tie of the present invention, therefore, retains its shape and is much more 105 convenient and durable than the ties heretofore made. It therefore has great utility. It will be understood that the term "tie" used herein is used in the broad sense and includes scarfs, mufflers, or any other similar articles of elongated form.

It will, of course, be understood, that various changes may be made in the form, details and proportions of the device, as well as in the steps of the method, without departing from the scope of applicant's invention which, generally stated, consists in a method and product capable of carrying out the objects above stated, and such as shown and described and set forth in the appended claims.

What is claimed is:

1. The method of producing a four-in-hand tie or similar article from a piece of fabric comprising laying out the patterns for said ties on said fabric, side by side, in 110

- alternate reverse arrangement with the center lines of said patterns extending at an angle of substantially 45 degrees to the warp of the goods, and then cutting said ties 5 from said goods.
2. The method set forth in claim 1, with the added steps of laying the alternately arranged patterns so that the piece of the goods therebetween will form the small end 10 portion of the tie.
3. The method of producing bias ties from a piece of goods comprising cutting the patterns of said ties from the goods with their center lines making an angle of 45 degrees 15 with the warp threads of the goods, folding each of the said patterns along its center line, stitching the folded edges together, turning the stitched tie inside out and arranging the seam in the center line at the 20 rear of the tie throughout the length thereof, whereby the center line of the pattern becomes the center line of the front or main portion of the tie.
4. The method of producing a four-in-hand tie or similar article comprising laying out the pattern for said tie on the goods by laying out a center line for said pattern extending at an angle of forty five degrees to the warp of the goods, and laying out the 25 sides of said pattern in straight lines making equal angles with said center line.
5. The method set forth in claim 4, with the additional steps of forming said pattern with a pointed triangular end, one side edge 30 of which is located in the selvage of the goods and the other side edge of which makes the same angle with the said center line as the first mentioned side edge and in- 35 tersecting the selvage a short distance from the intersection therewith of said center line 40 whereby a strip is left along said last mentioned side edge for hemming.
6. A four-in-hand tie or similar article having its longitudinal center line extending at a bias of 45 degrees relatively to the 45 goods, whereby the length of the warp thread passing through any point in said center line is the same as that of the woof thread passing through the same point and twisting of said tie is prevented. 50
7. A four-in-hand tie or similar article the main tying portion of which is formed from a folded integral piece of goods having a seam at its rear side and extending substantially along its longitudinal center line and the warp and woof threads passing through any point on said center line being 55 of equal length.
8. The method of laying out and forming a four-in-hand tie which consists in using a 60 tapered pattern with rectilinear side edges, placing the same diagonally upon a strip of goods in spaced oppositely disposed positions to form large pieces for the main portion of the tie, dividing the piece between 65 said pieces along a diagonal making a small angle with the sides of said larger pieces to form small pieces for the small end of the tie, folding said large and small pieces in two plies, joining the edges and arranging the seam to extend longitudinally and centrally along one side thereof and securing 70 said small piece to one side edge of the folded larger piece adjacent its small end.

In testimony whereof I affix my signature.
M. C. KELLY.
